UNITED STATES PATENT OFFICE.

OGLESBY ALLEN, JR., OF CHICAGO, ILLINOIS.

RAIL-JOINT.

1,092,624.

Specification of Letters Patent.

Patented Apr. 7, 1914.

Application filed May 15, 1913. Serial No. 767,848.

To all whom it may concern:

Be it known that I, OGLESBY ALLEN, JR., citizen of the United States, residing at Chicago, in the county of Cook and State of Illinois, have invented certain new and useful Improvements in Rail-Joints, of which the following is a specification.

My invention relates to new and useful improvements in rail joints and the object 10 of my invention is to provide means for securing the abutting ends of rails together without the use of bolts or other detachable fastening devices of like nature.

A further object of my invention is to 15 provide a fastening device of the above described character which will not only fasten the rail ends to each other but which will also provide for a reasonable expansion of the rails during hot weather.

20 A further object of my invention is to construct a fastening device which permits the ready removal of one or more rails from the track at any time in case of injury or the like. And a still further object of my 25 invention is to provide a construction by which standard rails may be employed in the track and which will require no change in the rail construction other than the cutting away of portions of the rail flanges and web, 30 no thickening of the rail web or recessing of the rail heads being required as is usually the case in rail fastenings of this character.

With these and other objects in view, my 35 invention will be more fully described, illustrated in the accompanying drawing, and then specifically pointed out in the claims which are attached to and form a part of this application.

In the drawing: Figure 1 is a central vertical longitudinal sectional view taken through my improved rail joint, the abutting rail ends being shown in elevation and the rail chair in section; Fig. 2 is a fragmentary perspective view of the rail chair 45 and of abutting rail ends, the parts being unassembled to more clearly show their construction; Fig. 3 is a transverse sectional view taken on the line 3—3 of Fig. 1, looking in the direction of the arrows.

50 Corresponding and like parts are referred to in the following description and indicated in all the views of the drawing by the same reference characters.

The preferred embodiment of my invention, as disclosed in the drawings, includes

a rail chair, indicated as a whole by the numeral 10, and adapted to receive and locking engage abutting rail ends. This chair is substantially rectangular in shape and equal in width to the width of the heads of 60 the rails to be fastened and in height to the height of the rails exclusive of the heads. The chair is provided with laterally directed tie engaging flanges 11 upon each side conforming in size and shape to the outer portions of the rail flanges and the body is provided throughout its entire length with a centrally disposed, longitudinally extending channel 12 forming resultant spaced walls 65 13 and 14 which are vertically disposed and 70 the upper edges of which are inclined inwardly to support the rail heads.

Referring more specifically to Fig. 1 of the drawing, it will be seen that the chair is provided centrally with a longitudinally extending shoulder or web 15 which is formed during the forming of the channel, being preferably cast integrally with the chair. The ends of this shoulder are preferably rounded somewhat as shown at 16 and the 75 shoulder is provided at points slightly spaced from its ends with substantially semicylindrical locking lugs 17. The ends of the base portion of the chair, including its flanges, are beveled downwardly away 80 from the center as shown at 18.

The entire chair above described, may be cast or otherwise formed in a single piece and at relatively low cost and in use may be secured to the ties of the track by spikes in 90 the same manner in which the rail chairs of the ordinary type are fastened.

The rails employed in connection with the above described chair are of the usual construction including a base having laterally directed flanges 19, a vertical web 20 and a head 21. In adapting them for use with the above described chair, the flanges 19 at the ends of the rails are cut-away, as is the base leaving the web and head of the 95 rails only. The free end of the web in either case is then cut-away as at 22 to engage against and over one end portion of the shoulder 15 and further cut-away as at 23 to engage over the locking lug 17. The web 100 of one of the abutting rail ends terminates flush with the head and is cut-away or mortised as at 24 to receive a tenon 25 formed upon the adjacent end of the next rail by the cutting away of the rail head and a portion 105 110

of the web. The construction of these parts will be readily understood from reference to Figs. 1 and 2 of the drawing and any further detailed description of the same is therefore unnecessary. It should be noted that the base and flanges of the rails are cut-away at an inclination to the vertical to conform to the beveled ends of the base and flanges of the rail chair and also that the cut-away portions 22 and 23 of the rail webs and the mortise 24 and tenon 25 thereof are so formed that when the rails are locked in position in the chair, as shown in Fig. 1, a slight longitudinal movement of each rail in the chair 10 is permitted. At the same time the engagement of the webs against the rounded ends 16 of the shoulder prevents movement of either rail through the chair, while the seating of the locking lugs 17 in the cut-away 15 portions 23 of the rail webs prevents the longitudinal withdrawal of either rail from the chair.

In laying the tracks the rails are fitted together end for end as shown in Fig. 1 of the drawing and a rail chair is then passed beneath the abutting rail ends and raised to seat its shoulder 15 and locking lugs 17 in the position shown in Fig. 1 when the rails and chair are both lowered into engagement 20 with the ties of the track and the chair spiked or otherwise secured thereto. The rails may at any time be separated from each other and from the chair by raising their abutting ends upward simultaneously when 25 the rail webs will be lifted from the channel of the chair and at the same time the tenon 25 will be withdrawn from the mortise 24. The weight of the rails themselves is sufficient to hold them firmly in place but if desired, of course bolts may be passed through 30 the walls 13 and 14 of the chair, which walls bear firmly against the opposite faces of the webs of the rails and through the webs of the rails. If this is done, the bores formed 35 in the rail webs should of course be made slightly elliptical with their major axes extending longitudinally of the rails to allow for the movement of the rails during expansion and contraction from changes in 40 temperature.

Although the above described structure constitutes the preferred embodiment of my invention it will of course be understood that various changes in the details of construction, within the scope of the appended 45 claims, may be made at any time, if desired,

without in the slightest degree departing from the spirit of my invention.

Having thus described the invention, what is claimed as new is:

1. A rail joint in combination, a chair having a longitudinal channel, a stop shoulder formed centrally of the channel, and abutting rail ends having their base and flanges cut-away to permit the seating of their web ends in the channel, said web ends being cut-away to engage about the shoulder and further cut away to provide interlocking tongue and mortise portions. 65

2. In a rail joint, the combination with a rail chair including a base having lateral flanges and vertically extending spaced apart walls, a stop shoulder formed centrally between the walls and locking lugs extending upwardly from the end portions 75 of the stop shoulder, of rails, the abutting ends of which have their flanges cut-away to permit the seating of their webs between the upstanding walls of the rail chair, said webs being cut-away for locking engagement with the shoulder and lugs thereof. 70

3. In a rail joint, the combination with a rail chair including a base having lateral flanges and vertically extending spaced apart walls, a stop shoulder formed centrally between the walls and locking lugs extending upwardly from the end portions of the stop shoulder, of rails, the abutting ends of which have their flanges cut-away to permit the seating of their webs between the upstanding walls of the rail chair, said webs being cut-away for locking engagement with the shoulder and lugs thereof, the web at one 85 end being provided with a mortise and the web at the other end with an extended tenon 90 seating in the mortise. 95

4. In a rail joint, a rail chair including a base having lateral flanges and vertically extending spaced apart walls, a stop shoulder formed centrally between the walls with its upper face parallel to the base, said stop shoulder being provided adjacent each end with an upstanding lug, and abutting rail ends having their flanges and web portions cut-away to permit their seating between the 100 upstanding walls of the rail chair. 105

In testimony whereof I affix my signature in presence of two witnesses.

OGLESBY ALLEN, JR. [L. S.]
